UNITED STATES PATENT OFFICE.

JOHN B. WALKER, OF BIRMINGHAM, ALABAMA.

EXPANSIBLE PATTERN FOR TUBULAR CASTINGS.

1,242,747.

Specification of Letters Patent.

Patented Oct. 9, 1917.

Application filed March 12, 1917. Serial No. 154,402.

To all whom it may concern:

Be it known that I, JOHN B. WALKER, a citizen of the United States of America, residing at Birmingham, in the county of 5 Jefferson and State of Alabama, have invented certain new and useful Improvements in Expansible Patterns for Tubular Castings, of which the following is a specification.

10 My invention relates to the art of making sand molds and cores for use in casting ingot molds, large pipe and like heavy tubular bodies.

15 My invention is especially (but not exclusively) adapted to form, in one operation by the use of a jarring table or jolt machine, both the sand core and the cheek or mold thus enabling me to greatly simplify and cheapen the cost of mold production and at 20 the same time to produce a standard of uniformity in the packing of both cheek and core that cannot reliably be obtained otherwise.

25 In the production of sand molds for ingot molds and the like I have heretofore used only a solid pattern and I have found by experience that in order to finally simplify the whole operation it is necessary to eliminate the careful, manual labor incident to the 30 stripping of the solid pattern from the sand core. A special object of this invention, therefore, is to provide a pattern that will expand and strip freely from the sand core when lifted by a crane and is so suspended 35 that its sections will, responsive to gravity action only, tend automatically to close or resume contracted position as soon as free of the core.

40 A further feature of my invention relates to the concealed means to limit the expanding movements of the pattern sections and to hold them positively against lateral displacement while leaving them free to part. I also provide novel means to prevent sand 45 from interfering with said limit means. This feature is of special importance where the core and cheek are formed simultaneously on the pattern, thereby requiring all fastenings to be of a concealed nature.

50 Where the cheek and core are simultaneously formed on a sectional pattern, it is essential to devise some simple and effective means for holding such pattern closed and this I accomplish by first forming as part of 55 the cheek an encircling band of packed sand

which surrounds the bottom of the pattern and holds the pattern sections closed together so that the packing of both core and cheek can thereafter proceed together. The advantage of such a method hardly needs 60 comment, for the stripping of the cheek will obviously free the pattern to expand when it is lifted to strip the core.

When a jarring process is used to pack the sand mold or cheek about an ingot mold 65 pattern, I have heretofore found it necessary to hand ram the sand under the outstanding lug patterns. A further object of my invention is to avoid this objectionable operation by leaving the pattern free of outstanding 70 projections which would interfere with the stripping of the cheek and providing detachable lug patterns adapted to seat in guide grooves formed in the top of the pattern so as to be free to strip vertically therefrom with the cheek.

As illustrative of the apparatus now regarded as the preferred embodiment of my invention, reference is made to the accompanying drawings, in which:

Figure 1 is a vertical sectional view taken on the line 1—1 of Fig. 3 and showing the core and cheek both rammed and the manner of detachably mounting the lug patterns.

Fig. 2 is an elevation of the flask broken 85 away to show the split edge of the pattern and illustrating the sand band for holding the same contracted during the ramming operation.

Fig. 3 is a top plan view of the assembled 90 apparatus.

Fig. 4 is a detail view showing the manner of applying the crane hooks to the pattern.

Fig. 5 is a detail view of the top of the 95 expandible core arbor.

Fig. 6 is a segmental view of the side edges of the pattern section showing the dowel pin and limit lug appliances for guiding and limiting the movements of the pattern sections.

Fig. 7 is a detail cross-sectional view taken through the bottom limit lug and stop plate therefor.

Similar reference numerals refer to similar parts throughout the drawings.

A jolt machine or jarring table 1 is formally illustrated and has mounted thereon a removable stool drag 2 to which the center column 3 of a collapsible core arbor 110

is secured by a wedge key 4. The arbor is formed by four collapsible staves 5 which carry at their upper ends internal socket bearings 5^a in which the pawls 5^b are mounted free to rock and disposed upwardly so as to engage the column 3 of the arbor at a point above the top of the staves. The staves have lapping corner joints as described in my pending application, Serial No. 86,920, and if desired only the staves carrying the inner flanges need be provided with the sockets 5^a and the pawls 5^b. The staves are expanded by the action of a plate 6 and wedge key 6^a on the column 3 which engages the pawls and forces the staves outwardly until arrested by the engagement of lugs 6^b on the staves with stop lugs 3^b on the column. The staves at their lower ends are mounted to rock in the sockets 2^b on the stool drag. The staves are operated to expand or contract the arbor, all as more fully described in my said application Serial No. 86,920. The stool is recessed in its upper face at 7 to form the drag portion of the mold. A stripping plate 8 is mounted on the stool drag and clamped in position to receive and center the lower end of the pattern which is shown of tubular form as generally used for the manufacture of ingot molds, though its shape can be modified for the manufacture of other articles. The pattern is substantially rectangular in cross section and is split diagonally through its corners in a vertical plane preferably into two half sections 9 and 10, each section carrying about its top edge a protecting plate 11 with upturned perforated lugs or ears 12 at each end. These lugs or ears are arranged to overhang so that the centers of their holes when in register will lie in the plane of parting between the pattern sections. Between each pair of lugs 12 I interpose a hanger plate 13 having a hole therein adapted to register with the holes in the lugs so that the bolts 14, which pivotally connect the lugs, will also hold the hanger plates in position between them. The upper free ends of these plates are provided with holes 15 to receive hooks 16 of the crane or hoisting tackle.

The pattern section 9 in each upper side edge is provided with a countersunk seat to receive a plate 17 carrying a dowel pin 18, and in its lower portion is a countersunk seat which receives a plate 19 having a stop lug 20 with a downturned hook 21 at its outer end. The side edges of the pattern section 10 have countersunk seats, the upper of which receive plates 22 having dowel pin holes 23 therein disposed to receive the dowel pins 18. The lower seats receive plates 24 having holes 25 into which the stop lugs 20 project with a close sliding side fit but with the bottom of the hole in position to clear the underface of the lug but

to engage the downturned hook 21 at the outer end of the lug. By this arrangement the lugs and the pins hold the flask sections against lateral displacement while permitting them to swing apart freely on their pivot bolts 14 until the hooks engage the plates 24, thus limiting the opening or expanding movement of the pattern. It is of importance to note that I provide the lower countersunk seats for the plates 24 with an opening 26 leading downwardly and at an incline outwardly through the face of the pattern, so that the sand can escape from the lug holes 25, it being essential that these holes shall not become packed with the sand as thereby the automatic closing action of the pattern sections might be interfered with.

The flask as described in my application Serial No. 136,642, is divided vertically into half sections 27 and 28, each having at its upper edge overhanging perforated lugs 29 which lap and each pair of which is hingedly connected by a pivot bolt 30. Each flask section carries a plurality of lifting lugs for engagement with the hoist tackle, the lugs 31 near the side edges being termed "closing" lugs and the lugs 32 being termed "opening" lugs.

The upper end of the column 3 is provided with a head 33 having a hole 34 for the crane or lifting tackle. Detachable hold-down bars 36 are interposed between the top of the pattern and the shoulders 35 at the top of the arbor column to prevent the pattern lifting with the cheek when it is raised to strip it therefrom. Such hold-down means form no part of my present invention and are illustrated merely to make clear the matter in which the tubular pattern that is otherwise free of fastenings, is held in position about the core while the cheek is being stripped therefrom.

Assuming the stool with the stripping plate, flask and core assembled thereon in position on the jarring table, the pattern is seated on the stool with its bottom end left free of any rigid fastening. Sand is first shoveled between the pattern and the flask to a height of about a foot, the jarring table is then operated to give the apparatus three or four jolts which compacts this sand about the pattern so that it will form an encircling sand band 45 which will force together and hold in that position the lower or free ends of the pattern sections. Having thus preliminarily secured the pattern in position, sand is filled in on both the inside and outside of the pattern and the jolting operation proceeds until the sand is packed practically to the top level of the pattern.

It will be observed that the pattern does not carry lugs for forming the ears or lugs on the ingot mold and my reason for leav-

ing the exterior of the pattern free of projections will be apparent when it is considered that my purpose is to pack the sand by the jolting or jarring process. If the lugs 5 were formed on the pattern it would be practically impossible to mechanically accomplish the proper packing of the sand under the lugs. In accordance with my present invention, the operator uses a shovel, 10 the blade of which is shaped so that when thrust downwardly into the packed sand around the top of the pattern, it will remove sufficient of the sand to form a seat which will receive the detached lug patterns 38 15 which are then set in position against the pattern sections 9 and 10. To insure the lug patterns being set in the right position, they are provided with tongues 39 that fit into vertical slots 40 in the pattern. After seating the lug patterns, additional sand is 20 thrown over them and rammed. When this has been accomplished, the crane is first applied, in the manner described in my pending application, Serial No. 136,642, to 25 lift the flask and strip the cheek from the pattern and stool drag and deliver it to foundry pits for finishing. The lug patterns will be stripped off with the cheek and can readily be drawn as part of the finishing operation. The crane hooks are then 30 applied to the hanger plates 13 of the pattern and, the encircling sand band which forms part of the cheek having been removed, the bottom end of the pattern is 35 released to expand to the full extent permitted by the stop lugs 20. As the pattern is lifted to strip it from the core, it will ride freely up the core and the latter will be thus protected from collapse or injury. 40 As soon as the pattern clears the core it can be set over another core arbor and the operation repeated, it being noted that the pattern sections will swing together into closed position by gravity as soon as they are 45 free of the core.

By utilizing the sand band for contracting the pattern I save one operation, required to contract and secure the pattern sections together and another operation to 50 release them so that the pattern can expand. It will be understood however that the sand band is only the preferred means, as my invention contemplates the use of any device or means which will hold the pattern contracted 55 during the ramming operation and which will strip with the cheek. In order to facilitate the stripping of the cheek, the pattern is preferably formed with a slight taper upwardly and this taper is effective 60 within the pattern also to facilitate its stripping from the core.

In view of divisional requirements my present invention is restricted to the construction of the expandable pattern and the 65 novel arrangement of detachable patterns

for projecting parts for use when the pattern is adapted for forming ingot molds on a jolt machine.

Having thus described my invention, what I claim as new and desire to secure by Letters Patent is:—

1. An expandable tubular pattern for hollow articles divided longitudinally into sections hinged at their upper ends, means to hold the sections, when contracted, against relative lateral displacement, and lifting members disposed to leave the pattern sections free to expand when suspended, substantially as described.

2. An expandable tubular pattern for hollow articles divided longitudinally into sections hinged at their upper ends, means to hold the sections, when contracted, against relative lateral displacement, lifting members disposed to leave the pattern sections 85 free to expand when suspended thereby, and means to limit the expanding movements of the lower ends of the patterns, substantially as described.

3. A sectional pattern for ingot molds and 90 the like divided on a vertical plane into sections, means to hingedly connect the sections at their upper ends, means to suspend the pattern from the hinges, and concealed means for holding the pattern sections 95 against relative lateral displacement.

4. A sectional pattern for ingot molds and the like divided on a vertical plane into sections, means to hingedly connect the sections, means to suspend the pattern from the 100 hinges, and concealed mechanisms mounted in the joint between sections for holding the pattern sections against relative lateral displacement.

5. A sectional pattern for ingot molds and 105 the like divided on a vertical plane into sections, means to connect the sections free to move toward or from each other, means to suspend the pattern, and concealed mechanisms mounted in the joint between sections 110 for holding the pattern sections against relative displacement, one mechanism comprising dowel pins and sockets for preventing the sections moving relatively laterally on each other, and the other mechanism comprising hook lugs and sockets for limiting the parting movement of the sections in expanding, substantially as described.

6. A sectional tubular pattern having its 115 inside and outside surfaces forming pattern 120 faces, said pattern being subdivided longitudinally and having in the abutting edge faces of the sections concealed means when the pattern is contracted for holding the assembled parts thereof in predetermined position.

7. A tubular pattern for ingot molds comprising a main body portion free of projection on its exterior side surface, and separate lug patterns slidably detachable from 130

and adapted for disconnected use with the main pattern, substantially as and for the purposes described.

8. In an apparatus for forming sand molds for ingot molds on a jarring table, a pattern for the ingot mold comprising a main body portion free of lug projections, vertical guide slots for the lug patterns, which slots extend up through the top of the pattern and are left open above, and detached lug patterns adapted to fit into and free to slide vertically out of said slots.

9. A tubular pattern for ingot molds and the like having its inside and outside surfaces forming pattern faces, said pattern being substantially rectangular in cross section and being split diagonally through corner edges to form vertical sections, and non-rigid connections for said sections which 20 permit them to move apart and expand the pattern.

10. In a pattern for ingot molds and like articles which is subdivided axially into sections, a non-rigid joint connecting the sections at their upper ends, coöperating lug and socket members in the abutting edges of the pattern sections, and sand ports leading from the sockets through the side of the pattern, substantially as described.

30 11. A pattern adapted for use on a jarring table for simultaneously forming the cheek and core for an ingot mold, said pattern being divided vertically into half sections, hingedly connected lugs at the top of the sections, a hanger plate hinged to each pair of lugs, the abutting edges of the pattern sections being provided near their upper ends with dowel pins, and sockets therefor, and near their lower ends with limit lugs and sockets therefor, there being sand escape ports from the limit lug sockets, substantially as described.

12. A tubular pattern for ingot molds and the like having its inside and outside surfaces forming pattern faces, said pattern being divided vertically into sections which are free to move relatively to expand or contract the pattern, and means in the joint to limit the expansion of the pattern, substantially as described.

50 13. A tubular pattern for ingot molds and the like having its inside and outside surfaces forming pattern faces, said pattern being divided vertically into sections, means 55 to connect the sections so that they are free

to move toward or from each other for the purpose of contracting or expanding the pattern, and means disposed in the joints of the sections to hold them against lateral displacement.

60

14. A tubular pattern for ingot molds and the like having its inside and outside surfaces forming pattern faces, said pattern being divided vertically into sections, means to connect the sections so that they are free to move toward or from each other for the purpose of contracting or expanding the pattern, and concealed means disposed in the joints and adapted to guide and limit the relative movements of the pattern sections, substantially as described.

65

15. In a molding apparatus, a pattern for ingot molds and the like which is divided vertically into sections, means connecting the sections so that they are free to move relatively and thereby expand or contract the pattern, and means adapted to be stripped from the pattern for holding its sections in contracted position in the mold.

70

16. In a molding apparatus, a pattern for ingot molds and the like having its inside and outside surfaces forming pattern faces, said pattern being divided into vertical sections, means connecting the sections so that they are free to expand or contract, and a sand band surrounding the pattern to hold it in contracted position in the mold.

75

17. A tapering tubular pattern for ingot molds and the like having its inside and outside surfaces forming pattern faces, said pattern being divided into vertical sections, means connecting said sections so that their lower ends are free to part, and means, forming part of the sand cheek and adapted to be stripped from the pattern therewith, 90 for holding the pattern contracted.

80

18. A tubular sectional pattern for ingot molds and the like divided longitudinally and having internal and external pattern surfaces for cheek and core, and means, carried by the portion of the pattern that is embedded in the sand, to guide and hold the pattern sections when contracted against relative movement except to expand the pattern, said means being disposed to leave said 105 pattern surfaces substantially undisturbed.

100

In testimony whereof I affix my signature.
JOHN B. WALKER.
